(57) CLAIM

We claim the ornamental design for a grasper, as shown and
described.

DESCRIPTION

FIG. 1 is a right, top perspective view of a grasper showing
the new design, with a pair of jaws in the closed position;
FIG. 2 is a right side view of the grasper of FIG. 1, showing
the pair of jaws in the closed position;
FIG. 3 is a left side view of the grasper of FIG. 1, showing
the pair of jaws in the closed position;
FIG. 4 is a top view of the grasper of FIG. 1, showing the
pair of jaws in the closed position;
FIG. 5 is a bottom view of the grasper of FIG. 1, showing
the pair of jaws in the closed position;
FIG. 6 is a front view of the grasper of FIG. 1, showing the
pair of jaws in the closed position;
FIG. 7 is a right, top perspective view of the grasper of FIG.
1, showing the pair of jaws in the open position;
FIG. 8 is a left bottom perspective view of the grasper of the
lower jaw of FIG. 7;
FIG. 9 is a right, top perspective view of the upper jaw of
FIG. 7;
FIG. 10 is a right side view of the upper jaw of FIG. 7;
FIG. 11 is a left side view of the upper jaw of FIG. 7;
FIG. 12 is a top view of the upper jaw of FIG. 7;
FIG. 13 is a bottom view of the upper jaw of FIG. 7;
FIG. 14 is a rear view of the upper jaw of FIG. 7; and,
FIG. 15 is a front view of the upper jaw of FIG. 7.

The broken line shown in the figures immediately adjacent
shading forms a boundary of the claimed design. The
portions shown in broken lines are included for the purpose
of illustrating environmental elements only. None of the
broken lines form part of the claimed design.
